UNITED STATES PATENT OFFICE

LESTER E. PADELFORD, OF BUFFALO, NEW YORK, ASSIGNOR TO THE REPUBLIC METAL-
WARE COMPANY, OF BUFFALO, NEW YORK, A CORPORATION OF NEW YORK

DESIGN FOR A TOASTING-MACHINE CASING

Application filed February 11, 1930. Serial No. 34,482. Term of patent 14 years.

To all whom it may concern:

Be it known that I, LESTER E. PADELFORD, a citizen of the United States of America, residing at the city of Buffalo, county of Erie, and State of New York, have invented a new, original, and ornamental Design for a Toasting-Machine Casing, of which the following is a specification, reference being had to the accompanying drawings, forming a part thereof.

In the drawings, Fig. 1 is a perspective

view of the front and side of the casing showing my new design, and Fig. 2 is a similar view of the back and opposite side of the casing.

I claim:

The ornamental design for a toasting machine casing as shown.

In testimony whereof, I have hereunto signed my name.

LESTER E. PADELFORD.
